SPOON OR SIMILAR ARTICLE

Burr Sebring, Barrington, R.I., assignor to Gorham, a
Division of Textron Inc., Providence, R.I.

Filed June 10, 1971, Ser. No. 152,006

Term of patent 14 years

Int. Cl. D7—03

U.S. Cl. D54—12 A

FIG. 2

FIG. 1

FIG. 3

FIG. 4

FIG. 5

FIG. 6

FIG. 7

FIG. 1 is a front elevational view of a spoon or similar article showing my new design,

FIG. 2 is an end elevational view thereof,

FIG. 3 is a right side elevational view thereof, the left side elevational view being a mirror image of the same,

FIG. 4 is a rear elevational view thereof,

FIG. 5 is an end elevational view opposite that of FIG. 2,

FIG. 6 is a cross-section on an enlarged scale taken on line 6—6 of FIG. 1,

FIG. 7 is a fragmentary front elevational view on an enlarged scale showing the design of FIG. 1.

The design is intended for use on sets comprising forks, spoons, knives, and similar articles of flatware.

I claim:

The ornamental design for a spoon or similar article, as shown and described.
